UNITED STATES PATENT OFFICE

149,984

DESIGN FOR A SWEATER

Frank M. Titelman, Altoona, Pa.

Application July 10, 1947, Serial No. 140,185

Term of patent 3½ years

(Cl. D3—4)

To all whom it may concern:

Be it known that I, Frank M. Titelman, a citizen of the United States of America, residing at Altoona, in the county of Blair and State of Pennsylvania, have invented a new, original, and ornamental Design for a Sweater, of which the following is a specification, reference being had to the accompanying drawing, forming a part thereof.

In the drawing, the drawing shows a front elevational view of a sweater embodying my design, the back of the sweater, except for the back portions of the sleeves, being plain.

I claim:

The ornamental design for a sweater, as shown and described.

FRANK M. TTELMAN.
